FLASHLIGHTS

Joseph Riotta, Brooklyn, N. Y.

Application February 6, 1953, Serial No. 335,573

2 Claims. (Cl. 240—10.6)

My invention relates to an improvement in flashlights and has for one of its objects to provide a flashlight which is of new and novel construction so as to enlarge its field of usefulness beyond that of similar devices of prior construction.

Generally speaking, my invention provides a flashlight in which a plurality of electric bulbs are employed, as distinguished from the conventional single bulb, these being arranged about the longitudinal axis of the flashlight. These additional bulbs have their own switch mechanism, so that they are operable independently of the central bulb, enabling the flashlight to be operated in the usual way or as a lantern, the housing or head of the flashlight being of translucent material about its sides, so that the rays from the additional bulbs will be projected through the sides of the housing instead of through its end.

In the accompanying drawings, wherein I have illustrated an embodiment of my invention,

Fig. 1 is a sectional elevational view of my improved device;

Fig. 2 is an isometric view of my device;

Fig. 3 is a section on the line 3—3 of Fig. 1; and

Fig. 4 is a fragmentary sectional elevational view taken substantially on the line 4—4 of Fig. 1.

Referring to the drawings in detail, 2 designates the metal case of my improved device, this case comprising a shank, a cap 6 for the outer end of the case, and a head 8. The head 8 is rolled to provide threads 10.

Within the head 8, across the bottom thereof, is an insulating disc or plate 12, which is held in place by a snap ring 14, which engages the side walls of the head 8.

The insulating disc 12 carries a central hollow contact member 16, which extends through the insulating disc, so that its lower end will contact the center terminal 18 of the inner battery 20 within the casing 2 from which the device is to receive its energy.

Secured to the upper face of the insulating disc 12, at each side of the contact member 16, are two bent spring contact arms 22 and 24. It is to be noted that these arms are so disposed upon the insulating disc that one end of each arm always engages the contact member 16.

Set into the threaded upper end of the head 8 and insulated therefrom is a sheet metal member providing reflectors 26 and 28 and sockets 30 and 32 for lateral bulbs 34 and 36. As will be apparent from the drawings, the sockets 30 and 32 overlie the laterally disposed contact arms 22 and 24, so that, when the bulbs 34 and 36 are in place, they will always engage the spring contact arms. As will be seen from the drawings, the reflectors 26 and 28 are so shaped that the light rays from the bulbs 34 and 36 will be reflected outwardly to one side of the longitudinal axis of the flashlight.

The reflector 38 for the central bulb 40 and the socket 42 for this bulb are integral with each other and are centrally disposed with respect to the metal member above referred to, which provides the lateral reflectors 26 and 28, a rubber grommet 39 being interposed between.

2

44 designates a contact rod, the lower end of which extends into the center contact member 16, the upper end extending upwardly of the flashlight as viewed in Fig. 1 through the center of the member providing the lateral reflectors 26 and 28 but out of contact with the reflector members. This contact member is spring-loaded by spring 46, and its upper or outer end projects beyond the reflector member sufficiently to make contact with the center contact of center bulb 40 when the latter is in place in its socket 42.

Screwed upon the head 8 of the flashlight case is a housing 48, preferably of translucent plastic, although any other suitable material may be used.

The combined reflector and lamp socket for the center bulb 40 are set into the top of this housing and are readily held in place by lens 50, which may be of glass or plastic, as desired.

The circuit for the central bulb is conveniently controlled by switch 52, mounted on the flashlight case, 20 the ground rod 54 being attached to this switch and movable endwise when the switch is closed to contact the reflector 38. This rod passes loosely through reflector 26, as will be seen from Fig. 4.

The circuit for the lateral bulbs 34 and 36 is controlled 25 by a similar switch 56, the ground rod 58 of this switch being movable endwise when the switch is operated to contact reflector 26.

In addition to all of the foregoing, my improved flashlight is provided with a device whereby the flashlight 30 may be made to stand upon a table or other support when both hands are in use. This device comprises spring arms 60, which are pivoted at their upper end to the case of the flashlight, as seen at 62. The tension of the arms is sufficient to enable the arms to be retained at any 35 angle desired with respect to the case 2, so that the flashlight will be supported at any desired angle. When the brace or arms are not in use, they may be closed upon the case 2, as illustrated in Fig. 1.

From all of the foregoing, it will be seen that I have 40 provided a flashlight which is novel in its construction in that the same may be used as a flashlight in the conventional way or as a lantern when desired or as the two combined. It is to be observed that the reflectors for the several light bulbs are so arranged that the light rays from the lateral bulbs 34 and 36 will be projected laterally from the head of the flashlight through the translucent housing 48 and are prevented from issuing through the end of the flashlight by the central reflector 38.

It will be seen that my improved device is simple in 50 construction, so that it may readily be disassembled and assembled for replacement of the light bulbs, etc.

It is to be understood that changes may be made in the details of my construction and arrangement of parts 55 within the purview of the invention.

What I claim is:

1. A flashlight comprising, in combination, a case, including a head; an insulating disc carried by the said head; a snap ring for holding the disc in place; a central contact carried by said disc; a battery in said case, said contact constantly engaging the central terminal of said battery; a pair of contact arms mounted upon said disc and constantly engaging said central contact; an element providing a pair of opaque reflectors and a pair of bulb sockets secured to said head in such position that a bulb 60 in each of said sockets will engage a contact arm; a housing of light-transmitting material carried by the said head whereby light rays from said bulbs will be projected by said reflectors through the housing laterally with respect to the longitudinal axis of the flashlight, the end 65 of said housing being provided with an aperture, a central opaque reflector and bulb socket in said aperture,
- 70

a lens for holding the last-mentioned reflector and socket in-place; a-spring-loaded-contact-rod-extending-from-the-said central contact and through the first-mentioned reflector-socket element so as to be engaged by the terminal of a bulb in said central socket; and switching mechanism carried by said case for controlling the circuits of the flashlight bulbs; said switching mechanism comprising a pair of ground rods movable endwise when the switch mechanism is operated, one ground rod passing through the first-mentioned reflector-socket element to engage 10 said central reflector, the other ground rod being movable endwise to engage the first-mentioned reflector-socket element.

2. A flashlight comprising, in combination, a flashlight case, including a head; a battery in said case; an insulating disc mounted in said head; a contact carried by said disc and engaging a terminal of said battery; a pair of contact arms mounted upon said disc in engagement with the first-mentioned contact; a member providing a pair of reflectors and a pair of lamp sockets mounted in said head above said disc, said reflectors and lamp sockets being 15

positioned at each side of the axis of said case, and the sockets being so disposed that bulbs carried thereby will constantly engage said contact arms; a translucent housing carried by the flashlight head, the sidewalls of said housing being in the path of light rays projected by said reflectors; an opaque reflector and a bulb socket disposed in the end of the housing axially of the flashlight case, and a lens secured in the end of said translucent housing in the path of light rays projected by the last-mentioned reflector, for holding the last-mentioned reflector and bulb socket in place in the housing end.
